UNITED STATES PATENT OFFICE.

KENNETH RUSHTON, OF PHILADELPHIA, PENNSYLVANIA, ASSIGNOR
TO BURNHAM, WILLIAMS & COMPANY, OF PHILADELPHIA, PENNSYLVANIA, A FIRM.

THROTTLE-VALVE.

SPECIFICATION forming part of Letters Patent No. 723,734, dated March 24, 1903.

Application filed March 27, 1902. Serial No. 100,212. (No model.)

To all whom it may concern:

Be it known that I, KENNETH RUSHTON, a citizen of the United States, residing at Philadelphia, Pennsylvania, have invented certain 5 Improvements in Throttle-Valves, of which the following is a specification.

The main object of my invention is to construct a throttle-valve for admitting steam from the boiler into the cylinders of a locomotive or other engine in which an auxiliary valve is used to admit steam to the cylinders while the locomotive, for instance, is drifting.

A further object is to wire-draw the steam through the valve-chamber, so that there will be a certain amount of back pressure under the main valve and that the said main valve can be more readily opened when desired.

In the accompanying drawings, Figure 1 is a sectional view through the valve and valve-chamber. Fig. 2 is a section on the line 2 2, Fig. 1. Fig. 3 is a sectional view showing the supplemental valve raised, and Fig. 4 is a sectional view showing the main valve raised.

25 A is the valve-casing, mounted in the steam-dome of the boiler, having a neck A', which is coupled to the steam-supply pipe B, leading to the cylinders of the locomotive in the present instance. On the upper end of this 30 casing is a seat a, and fitting the seat is the main valve D. This valve has wings d extending down to a ring d', which closes openings a', leading to the neck A'. These openings a' are formed in the body of the valve-chamber A, as is also a small opening a², preferably near the base of the said chamber, as clearly shown. This opening also communicates with the neck. The valve D is carried

40 by a stem E, which passes through a central opening therein, the walls of the opening forming a seat d², and on the stem E is a supplemental valve e, which fits on the seat. On the lower end of the stem are a nut and washer to provide a certain amount of lost motion in 45 the stem, so that the supplemental valve e can be raised off its seat on the main valve before the main valve is raised off its seat.

F is a lever pivoted at f to a projection on the valve-casing, and the stem E is connected 50 to this lever. The lever in turn is connected

by a link F' to a bell-crank lever F², also pivoted to a lug on the frame and connected to an operating-lever in the cab of the locomotive in the ordinary manner.

The area of the opening a² in the valve-casing is much less than the area of the opening formed between the small valve and its seat when the said valve is opened, so that the steam is wire-drawn from the valve-casing into the neck A'. This necessarily makes a 55 certain amount of back pressure in the casing A, so that there will be a pressure under the main valve to counteract to a certain degree the pressure on top of the main valve, so that when it is desired to open the main valve it 60 will open more readily owing to the fact that it is partly balanced; but when both valves are closed the main valve is held firmly down to its seat by the boiler-pressure.

It will be seen by using my improved throttle-valve, which is especially adapted for locomotives, the engineer can close his main valve and open the auxiliary valve, as in Fig. 3, to allow a certain amount of steam to be admitted to the cylinders when the locomotive is drifting, and there is a greater amount of steam admitted than can pass from the valve-chamber through the opening a². Consequently there is a certain amount of back pressure within the valve-casing A, so that 75 when it is desired to open the main valve this back pressure will aid in the opening, Fig. 4, as it will tend to counterbalance the boiler-pressure on the outside of the valve, thus making it much easier for the engineer to 80 open the valve than where the valve is not balanced.

I claim as my invention—

1. The combination in a throttle-valve of a valve-casing, a steam-supply pipe, a main valve adapted to a seat in the valve-casing, a supplemental valve adapted to a seat in the main valve, said valve-casing having a main outlet and a supplemental outlet to the steam-supply pipe, the area of said supplemental 90 outlet being less than the area of the opening of the supplemental valve, substantially as described.

2. The combination of the steam-supply pipe, a valve-casing having an inlet-opening 95

communicating with the steam-chamber and an outlet-opening communicating with the steam-supply pipe, a valve arranged to close both the inlet and outlet openings and a supplemental valve seated on the main valve, said valve-casing having a supplemental outlet to the steam-supply pipe, said supplemental outlet being of an area less than that of the opening closed by the supplemental valve, substantially as described.

3. The combination of a valve-casing having an inlet-opening, outlet-openings, a main valve having a portion closing the inlet-opening, and having a ring portion closing the outlet-openings, a stem upon which the main valve is mounted, said stem carrying a supplemental valve having its seat on the main valve, said stem having a certain amount of lost motion so that when the stem is moved it will first raise the supplemental valve off its seat and then the main valve, the casing having a supplemental outlet-opening less in area than the opening of the supplemental valve, substantially as described.

4. The combination of a valve-chest having an inlet-opening at the top and outlet-openings communicating with the passage leading to the cylinders, a valve having a main portion arranged to close the inlet-opening and having a ring portion arranged to close the outlet-openings, a stem passing through the main portion of the valve and having the supplemental valve mounted thereon and seated in an opening in the main valve, said stem being connected to the main valve so as to allow the supplemental valve to be elevated off its seat before the main valve is opened, with a supplemental outlet-opening from the valve-chest leading to the passage communicating with the cylinders, substantially as described.

In testimony whereof I have signed my name to this specification in the presence of two subscribing witnesses.

KENNETH RUSHTON.
